SHIP STABILIZING CONTROL SYSTEM

Erling Frisch, Pittsburgh, and Walter Schaelchlin, Wilkinsburg, Pa., and John H. Ashbaugh, Springfield, Mass., assignors to Westinghouse Electric and Manufacturing Company, a corporation of Pennsylvania

Application June 9, 1932, Serial No. 616,256

5 Claims. (Cl. 74—5)

Our invention relates to gyroscopic stabilizing systems for limiting or preventing the rolling motion of vessels and it has particular relation to methods and apparatus for controlling the precession thereof.

One object of our invention is to provide control equipment of the kind referred to wherein energy from the waves, or from the rolling of the ship, is regenerated through the precession motor.

A further object of our invention is to prevent the effective regenerative effect of the precession motor from exceeding a predetermined value.

It is also an object of our invention to keep the speed relation between the spinning motor for the gyroscope and the generator supplying the spinning motor within predetermined limits.

A more specific object of our invention is to provide for a dynamic braking effect in a precession motor and for weakening the excitation of a precession-generator supplying energy to the precession motor to maintain the speed relation between a gyroscope spinning motor and a spinning-generator supplying energy to the spinning motor substantially constant.

A further object of our invention is to stop a precession motor when the speed of a generator supplying energy to a gyroscope spinning motor exceeds a predetermined value.

It is also an object of our invention to prevent over-travel or "hunting" of a precession motor.

A still further object of our invention is to decelerate a precession motor in two successively more effective steps.

It is also an object of our invention to provide a simple control system whereby the entire stabilizing operation may be automatically accomplished with a minimum of apparatus.

With these and other objects in view, our invention consists in the details of construction and in the methods of manipulation described in the following specification and covered by the appended claims, and illustrated in the accompanying drawings, wherein:

Figure 1 is a diagrammatic view of circuits and apparatus embodying our invention in preferred form;

Fig. 2 is a side view, looking from left to right, of the main gyroscope and housing, showing the mechanical buffers and the limit-switch tripping devices;

Fig. 3 is a diagrammatic showing of a scheme associated with the control gyro to prevent hunting of the precession motor;

Fig. 4 is a modified showing of the directional

contactors, showing them provided with mechanical interlocks;

Fig. 5 shows a graduated dynamic braking circuit for the main motor; and

Fig. 6 shows a connection for the precession motor and direct current generator to produce an artificial roll of the vessel.

Referring more particularly to Figure 1 of the drawings, 1 designates a main stabilizing gyroscope which is horizontally pivoted on gudgeon bearings 140 disposed athwartship whereby the stabilizing forces may be transmitted to the frame structure of the vessel. The gyroscope further comprises a casing in which casing is mounted a flywheel 33 which is supported in thrust bearing 141 and bearings 151 and which is driven by a squirrel-cage spinning motor 2. Connected to the casing is an arcuate gear member 142 which is in operative relation to a pinion 143 mounted on the shaft of the precession motor 5 and which is in operative relation with a pinion 160 for operating the limit-switch mechanism 161.

The spinning motor 2 is supplied with energy from an alternating current generator or alternator 3, which in turn is driven by a turbine 4. A precession motor 5 is mechanically coupled to the arcuate gear member 142, as above specified, and the precession motor 5 is supplied with energy from a direct current generator 6 coupled to the shaft of the alternating current generator.

A mechanical brake 7, which may be released by an electromagnetic arrangement, is mechanically coupled to the precession motor and the precession motor is controlled in the direction of rotation by a control gyro 8.

To accomplish the desired controlling effect, an electrical control system is provided consisting of a pair of directional contactors 11 and 12, a control contactor 13, a dynamic braking contactor 14 and a generator field neutralizing contactor 15. To further control the operation of the various elements, a power limit relay 63, a limit-switch mechanism 161 and an overspeed mechanism 26 are provided.

To more clearly understand the operation, as well as the novel features of our invention, a study of the sequence of operation will now be given.

Assuming that conductors 16 and 17 are supplied with direct current energy from a suitable source and that the attendant closes the double pole knife switch 18 to energize conductors 9 and 10, a circuit is established from the energized conductor 9 through conductor 20, actuating

coil 21 of the main line contactor 22 disposed in the circuit leading from the alternating current generator 3 to the spinning motor 2 through the slip rings 32, rings 23 and 25 bridged by the 5 spring biased contact member 24 of the overspeed device 26, conductor 27 to the energized conductor 10.

A second circuit is also established from the 10 energized conductor 9 through conductor 28, field rheostat 29, field winding 30 of the alternating current generator 3 and conductor 31 to the negatively energized conductor 27.

The field winding 30 of the alternating current generator is provided with a high resistance discharge resistor 30' which prevents damage to the insulation of the field winding when 15 double pole switch 18 is opened. The field rheostat 29, during the starting operation, should be adjusted to a maximum excitation so that the 20 voltage of the generator 3 will be a maximum during the initial stages of its rotation when the frequency of the generator is low.

If the generator has been excited, as hereinabove stated, steam is admitted to the turbine 4 25 and the generator will build up a voltage as the speed of the turbine increases. At a speed corresponding to approximately 3 cycles a second a sufficiently large torque is developed at the spinning motor to overcome the static friction 30 of the flywheel 33 which, consequently, will start turning at a slowly increasing speed. As the speed increases the torque margin between the generator 3 and the motor 2 will increase and the generator field can be weakened. Further, 35 as the speed of the spinning motor and generator increases to high values the field winding 30 of the generator 3 should be excited less and less.

When the main stabilizing gyro 1 has attained 40 its normal operating speed the double pole knife switch 34 is actuated thereby energizing the buses 35 and 39.

Energization of the buses 35 and 39 establishes 45 a circuit from the bus 35 through field rheostat 36, motor field 37 and conductor 38 to the bus 39. When the buses 35 and 39 are energized the control gyro 8 also starts operation since the motor 40 driving the gyro wheel 41 is directly connected to the buses 35 and 39. The control gyro is 50 a relatively small unit and the gyro wheel 41 operates at a comparatively high speed so that its sensitivity may be great. The shaft of the gyro wheel 41 is disposed athwartship so that the casing of the control gyro, which is spring 55 biased in the manner shown, may be caused to oscillate when the vessel rolls. It should be noted that the motor for the control gyro and the field winding 37 for the precession motor 5 cannot be energized unless the switch 18 has 60 been closed, thereby exciting the field winding 30 of the alternating-current generator 3 supplying the energy to the spinning motor 2.

If the ship is rolling the spring biased contact member 43 is brought into contact relation with 65 either contact member 42 or contact member 98, depending upon the direction of roll of the vessel. Assuming that the vessel rolls in such a direction that the spring biased contact member 43 engages the contact member 42, a circuit is thus 70 established from the energized conductor 35 through conductor 41', contact members 43 and 42, actuating coil 44 of directional contactor 11, limit-switch 45, limit-switches 46 and 47, conductor 48, contact members 49, which were 75 closed when the line contactor 22 operated, con-

ductor 50 and actuating coil 51 of the control contactor 13 to the energized conductor 39.

It should be noted that operation of the control contactor 13 releases the brake 7 holding the precession motor 5 in place. The circuit for 5 the brake releasing coil 57 may be traced from the energized conductor 35 through contact members 52 of control contactor 13, conductor 53, contact members 54 on the brake releasing mechanism connected in parallel to the resistor 10 55, resistor 56, actuating coil 57 for the mechanical brake 7, conductors 58 and 59 to the energized conductor 39. While we have shown but a single brake 7 in actual practice, more often a plurality of brakes are utilized so that the stopping 15 of the precession motor may be effected in a very short interval of time particularly when coacting with the regenerative braking and dynamic braking effect, more specifically discussed hereinafter, which are set up in the precession 20 motor. The brake releasing coil 57 is provided with a discharge resistor 156, which may be adjustable for varying the time constant of coil 57.

A second circuit is established by the operation 25 of the control contactor 13 which circuit may be traced from the energized conductor 35 through contact member 60 of contactor 13, conductor 61, contact members 62 and 64 of the power limit relay 63, actuating coil 65 of the contactor for 30 shunting the generator field resistor 76 and conductor 66 to the energized conductor 39. A further circuit is established from contact member 60 through actuating coil 67 of dynamic braking contactor 14, which coil is connected in 35 parallel to a discharge resistor 68, actuating coil 69 of the generator, field neutralizing contactor 15 which latter coil is connected in parallel circuit relation to discharge resistor 70, to the energized conductor 66. It will be noted that operation of 40 the contactor 14 removes the dynamic braking resistor 68 and contact members 67 from the circuit of the precession motor and that operation of contactor 15 removes the circuit through resistor 185, differential series field winding 186 45 and contact members 187 from the generator 6.

The operation of the directional contactor 11 also establishes a circuit from the energized conductor 35 through conductor 71, contact members 72 of directional contactor 11, conductor 73, 50 generator field winding 74, contact members 75, field rheostat 71, conductors 78 and 79, contact members 80, limit-switch 81 connected in parallel circuit relation to a field circuit resistor 82 and conductor 59 to the energized conductor 39. 55 From the circuits just traced it is apparent that the circuit for the field winding of the generator 6 is established, that the generator 6 is running at normal operating speed, that the field 37 of the precession motor is excited, that the armature of 60 the precession motor 5 is connected in closed circuit relation with the generator 6 by a circuit through conductor 83, commutating field 19 for the precession motor 5, the precession motor armature and conductor 84 back to the generator 6. The field winding 74 is designed so that the excitation builds up slowly thereby limiting the starting current for the precession motor 5.

In the beginning of a rolling cycle with the precessing motor in operation, energy is absorbed by 70 the precession system and the flow of energy is, therefore, from the generator to the motor. Shortly after the motor has reached full speed, however, energy will be generated in the precession system with a result that the precession 75

motor will act as a generator and transfer energy to the direct current generator 6 which will then work as a motor. This energy will be mechanically transferred to the alternating current generator 3 and will finally be absorbed in the fly-wheel 33 of the main stabilizing gyro 1.

If the energy transferred from the alternating current generator 3 to the spinning motor 2 becomes too great, the generator may be pulled out of step with the spinning motor. This must, of course, be avoided and a power limit relay is provided in the precession motor circuit to limit the reverse flow of power. When the power reaches the limit for which the relay has been adjusted, the relay will operate and shunt out coil 67 of the dynamic braking contactor 14 with the result that the contact members 87 will close and insert the dynamic braking resistor 86 in the circuit of the precession motor. The shunt circuit for the actuating coil 67 extends from the energized conductor 61 through contact members 62 and 93 to the actuating coil 69 of the contactor 15.

The power limit relay 63 is provided with a movable armature pivoted at a given point and spring biased to keep the contact members 62 and 64 in engagement when the coil 92, mounted on the movable armature, acts in opposition to the coil 89 mounted on the magnetic frame of the power limit relay. If it be assumed that the conductor 84 is the positive conductor for the particular operation of the directional contactor 11 above described, current flow takes place from conductor 84 through resistor 86, coil 89 of power limit relay 63 and conductor 90 to the negatively energized conductor 83. Since, for normal operation, that is, motor operation for the precession motor 5, the flow of current will be from the lower armature terminal of the precession motor through the commutating field winding 19 and conductor 83 to the upper armature terminal of the generator 6. The coil 92 will thus be energized from the upper terminal of the commutating field winding 19 through current limiting resistor 91, coil 92 and conductor 90 to the lower terminal of the commutating field 19. The magnetic action of the coils 89 and 92 will thus be as indicated by the full line arrows shown adjacent these coils. When the regenerative effect of the precession motor 5 exceeds a predetermined value the current through the commutating field 19 is reversed and coil 92 is then energized to act accumulatively with coil 89 which will obviously still be energized in its original direction. The power limit relay is thus operated and establishes the shunt circuit for actuating coil 67 and discharge resistor 86 above described.

The shunting of coil 67 closes the contact members 87 connecting the dynamic braking resistor 86 in circuit with the precession motor 5.

In order to prevent the direct current generator 6 from feeding back to the resistor 86 and also to prevent a rise in the speed of the precession motor 5, the generator field 74 must be somewhat weakened. Since the power limit relay operates to close contact members 62 and 93, the circuit for actuating coil 65 of the resistor shunting contactor is opened whereupon the contact members 75 open to insert the resistor sections 76 in the field winding 74. As soon as the power flow from the motor 5 to the generator 6 again drops below a predetermined limit, the power limit relay operates in the reverse direction, thereby effecting disconnection of the dynamic braking resistor 86. The precession motor 5, therefore, is braked only by its regenerative brak-

ing effect therein. For the particular installation we have in mind for this invention, it should be noted that for an operation with a maximum rolling of 5° the regenerated energy will be below the permissible limit and no dynamic braking of the precession motor 5 will be required. It is, of course, obvious, that operation of the power limit relay 63 to the position shown again energizes coil 65, thereby effecting stronger excitation for the field 74 of the generator 6.

When the end of the roll of the vessel is reached the contact members 42 and 43 will move to open circuit position, thereby deenergizing the control contactor 13 and the directional contactor 11 disconnects the field 74 of the generator 6 from the buses 35 and 39 whereupon the excitation of the field of the generator discharging through discharge resistor 174 approaches zero. The voltage of the generator will thus rapidly drop below the voltage of the precession motor, and regenerative braking of the motor will take place during the decay of the field excitation of the generator and the precession motor will slow down rapidly. Substantially simultaneously with the interruption of the field circuit of the generator, the actuating coils of contactors 13, 14, and 15 and the actuating coil 65 will be deenergized. Interruption of the circuit, at contact members 52 deenergizes the brakes 7 whereupon the brakes are applied to the precession motor a predetermined time interval after opening of contact members 52, the time interval depending upon the adjustment of the discharge resistor 156 and the inductive characteristics of coil 57. Opening of the contact member 60 effects the closing of contact members 87 thereby establishing the dynamic braking circuit for the precession motor and closing of the contact members 187 establishes the circuit through the differential series field 186. The differential series field winding 186 for the generator 6 is designed to substantially entirely neutralize the residual magnetism in the pole pieces of the generator 6, thereby preventing excessive circulating currents through the armature of the precession motor when that armature is locked into position by the brakes 7.

From the foregoing description, it is obvious that the voltage of the generator 6 rapidly decreases substantially to zero, during which time, depending on the inductive characteristics of the field 74 and the resistance value of the discharge resistor 174, a regenerative braking effect is established in the motor 5, thereafter a low resistance dynamic braking circuit is established for the precession motor, and when the precession motor has come nearly to rest the brake 7 acts to stop, in fact, substantially lock the precession motor 5 in position. It is thus obvious that the precession motor will be brought to rest very rapidly.

The actuating coil 69 of the generator field neutralizing contactor is provided with a discharge resistor 70 having a much lower resistance value than the discharge resistor 68 of the dynamic braking contactor 14. The result is that the current in coil 69 will decrease at a slower rate than the current in the coil 67. The stopping operation of the precession motor 5 is thus effected in three distinct steps, namely, a regenerative braking effect immediately followed by a dynamic braking effect which is thereafter aided by the brakes 7.

During the braking period which will last only about .4 second, the vessel starts to roll in the

opposite direction and the contact members 43 and 98 will close, thereby starting the precession in the opposite direction. In order to prevent the field contactors 11 and 12 from being closed 5 while the precession motor 5 may still be running in the reverse direction, the contactors 11 and 12 are provided with additional coils 96 and 95 respectively, which, when energized, will hold the contactors in open position. Coils 95 and 96 10 are connected across the armature terminals of the precession motor and will thus remain energized until the voltage of the motor and consequently the motor speed has dropped to a very low value. (After the contactors 11 or 12 are 15 closed, their respective coils 96 and 95 exert a force which is not sufficient to open the contactors and the contactors will, therefore, remain closed until the main coils are deenergized.) In actual practice, the directional contactors may 20 be mechanically interlocked in a well known manner, as by bar 200, as shown in Fig. 4, to prevent simultaneous operation of both contactors and thus establish a short circuit across the buses 35 and 39.

25 The shunt brake is provided with auxiliary contact members 54 which will open when the brake is released by the energization of the coil 57 thereby inserting resistor 55 in the circuit of the coil 57. The resistance value of this resistor is so selected that the current through the coil 57 is decreased just sufficiently to hold the brake shoes in the released position. Since the current necessary to hold them in released position is but a fraction of the current required to release the 30 brakes, a saving of electricity is made and, what is more important, the time to apply the brakes is decreased to a minimum when it is desired to stop the precession motor. It is very important that a very short time be allowed to bring the 35 precession motor from full speed to a dead stop and the circuit arrangement just discussed provides a means for accomplishing just this purpose.

When the control gyro closes the contact members 43 and 98, a circuit is established from the 40 energized conductor 35 through conductor 41', contact members 43 and 98, actuating coil 99 of directional contactor 12, limit switch 100, limit switches 46 and 47, conductor 48, contact members 49, conductor 50, actuating coil 51 of the 45 control contactor 13 to the energized conductor 39. Operation of the directional contactor 12 establishes a circuit from the conductor 35 through contact members 101, conductors 79 and 78, field 50 rheostat 77, contact members 75 which will, of course, be immediately closed after the operation of the control contactor 13, field winding 74, conductor 73, contact members 102, conductor 103, limit switch 105, to the negatively energized conductor 55. Connected in parallel circuit relation to limit switch 105 is a field discharge resistor 104 which may be included in the field circuit of the generator 6 when limit switch 105 is operated 60 in the manner discussed more in detail hereinafter. It will be noted that the operation of the directional contactor 12 energizes the field 74 in reverse direction and the precession motor will be actuated in the reverse direction by the control elements heretofore discussed which operate in every detail in the manner described in the foregoing discussion of the operation of the precession motor for the direction of roll of the vessel first assumed.

The precession angle of the main gyroscope 75 from a vertical position must not exceed a cer-

tain value. To prevent overtraveling of the precession motor, the limit-switch mechanism 161 is provided. One pair of limit-switches 81 and 105 is mounted so as to open when the precession angle reaches approximately 45°, that is, when the housing for the main stabilizing gyroscope 1 has been moved through an angle 45° from the vertical position shown. When limit switches 81 or 105 are opened, depending upon the direction of overtravel, resistor sections 82 and 104, as the 10 case may be, will be inserted in circuit with the field winding 74, thereby reducing the generator voltage and, consequently, the speed of the precession motor by approximately 20%. Another set of limit switches 45 and 100 is located in the 15 main control circuit and will cause the precession motor to stop when opened. These switches are located at about 60° of precession angle.

As an additional safety, the gyroscope is provided with mechanical buffers 109 which will limit 20 the travel to 72°. When the buffers are utilized to limit the travel the cutout switches 46 and 47 in the main control circuit are caused to operate, and the gyroscope will be latched in this position and must be released by hand. In this connection, attention is called to Fig. 2 showing an end view of the main gyroscope 1. This end view shows the resilient mechanical buffers 109 which coact with the stops 110 on the housing of the gyroscope. Cooperating with the mechanical 25 buffers are the latching members 46' and 47' which are designed to cooperate with latching dogs 111 to latch the main housing of the gyroscope in its extreme position.

When the ship is subjected to excessive rolling, 30 the successive braking effects may not be sufficiently effective to prevent an over-traveling of the precession motor. The precession motor may, in spite of the fact that it becomes deenergized when the casing of the gyroscope has moved 35 through 60°, continue to rotate until the casing has moved to about 72°. When such is the case, injury may result to the equipment and it is best to lock the casing in position by the latching means 46' or 47'. To assure that the precession 40 motor remains deenergized, switches 46 or 47, depending upon the direction of excessive oscillation, are opened and in consequence the portion of the system controlled by the direction contactors 11 and 12 remains deenergized.

In order to prevent excessive speeds of the gyroscope an overspeed device 26 is provided which will open the circuit for the main line contactor 22 disposed in the circuit intermediate the spinning motor 2 and the alternating current 45 generator 3. The opening of this circuit will deenergize the coil 21 and thus cause disconnection of the spinning motor 2 from the generator 3. Since contact members 49 are mounted on the 50 main contactor 22 the circuit for the control system of the precession motor and the generator, therefore, is interrupted and the precession motor is also caused to stop in a manner similar to the stopping operation heretofore discussed.

In order to shorten the time needed to slow 55 down the flywheel 33 when stabilizing of the ship is no longer required a special three phase dynamic braking resistor, having resistor elements 106, 107, and 108 is provided. This braking resistor may be connected, through knife 60 switches 112 to the slip rings 32 for the spinning motor 2. When energy is no longer supplied to the spinning motor 2 from the generator 3 the spinning motor will act as an induction generator 65 receiving its magnetizing current from the syn- 75

chronous generator. The energy generated by the spinning motor is thus dissipated in the resistor sections 106, 107, and 108 and the flywheel 33 of the gyroscope 1 is brought to rest. The 5 resistor sections 106, 107, and 108 may be provided with a plurality of switches 212 as shown in Fig. 5, whereby the resistance value thereof may be successively reduced to provide a graduated dynamic braking for the flywheel 33.

10 It is, of course, obvious that if it is desired to create an artificial roll of the ship a small double throw knife switch 300, as shown in Fig. 6, may be provided in the main control circuit which switch may be operated to successively 15 operate the precession motor 5, first in one direction and then in another direction until the desired roll of the vessel is accomplished.

20 To prevent hunting of the precession motor by reason of the control action of the control gyro 8 the additional features shown in Fig. 3 may be provided. Reference character 115 shows a pendulum suspended from a pivot at 116 and which pendulum through a link 117 and a bell crank lever 118 actuates a piston 119 in the cylinder 120. A substantially non-compressible liquid is placed in the cylinders 120 and 123. With reciprocations of the piston 119, liquid is transmitted to the cylinder 123 through tubes 121 and 122 and in so moving between the cylinders 30 piston 124 is reciprocated in a vertical direction and by rod 125 actuates the lever 128 pivoted at 129. The cylinder 123 is provided with a bypass conduit 126 provided with a valve 127. When the anti-hunting feature shown in Fig. 3 is not to be utilized, valve 127 may be opened, whereupon movement of the pendulum 115 will be ineffective to move the pivoted lever 128.

When the ship rolls the pendulum, which is disposed to swing athwartship, operates the lever 128 to bring either of the contact members 42 and 98 in contact relation with contact member 43 depending upon the direction of roll of the vessel. The levers 131 and 132 pivoted at 135 are biased to engage the stop 130 by the spring 134. From the arrangement shown it is obvious that after any given oscillation the lever 128 will always be repositioned to a neutral position so that the main controlling effect of the control gyro 8 is not impaired. With the arrangement shown in Fig. 3 the contact members 42 and 98 may be positioned more closely to the contact member 43 than for the showing in Fig. 1 thus aiding in preventing the control gyro 8 from effecting a hunting of the precession motor.

55 It is to be understood that the description of our invention herein given is merely illustrative and that the circuit arrangements may be modified and the controlling effect modified without departing from the spirit of this invention as defined in the appended claims.

We claim as our invention:

1. In a control system the combination including an electric motor having an armature winding connected to drive a gyroscope, and a field winding, a generator having an armature and a field winding, means for energizing said field windings, means for connecting the said armatures in closed circuit relation, means to de-energize the said generator field winding, there- 65 by establishing a regenerative braking action in the motor, two means operable successively for initiating a dynamic braking action and a mechanical braking action, and means for reducing the field flux of the field winding of the generator to substantially zero during such braking.

actions, thereby preventing the circulation of a large amount of current through the armature of the motor when it is brought to rest by the braking actions.

2. In a control system for a gyroscopic stabilizer comprising a spinning motor for driving the gyroscopic wheel, a precession motor mechanically coupled to the gyroscope wheel and adapted to vary the position of the gyroscopic wheel to counteract the force tending to disturb the balance of the stabilizer, a generator electrically connected to the spinning motor for delivering electrical energy thereto, a second generator electrically connected to the precession motor, means for driving the said generators, means for mechanically interconnecting the said generators, means for changing the relative circuit arrangements between the spinning motor and the generator therefor, for regeneratively arresting the rotation of the precession motor, thereby, 20 through said second generator, operating as a motor, and the mechanical interconnection between the generators, utilizing the force tending to disturb the balance of the stabilizer to drive the spinning motor, and means for utilizing a predetermined amount of the force tending to disturb the balance of the stabilizer to drive the spinning motor, thus preventing the overloading of the second mentioned generator when operating as a motor. 30

3. Control means for controlling the operation of a gyroscopic stabilizer for a vessel, comprising, in combination, a direct current precession motor having an armature, a generator permanently connected to the armature of said motor, 35 field windings for said motor and generator, respectively, means for driving the generator or for absorbing energy therefrom during regenerative operation of the motor, means to supply exciting-current to said motor and said generator, means whereby the field windings of the motor and the generator may be excited, a reversing switch and circuits connecting the field winding of the generator across said source to energize the same in the one direction or the other, a dynamic braking circuit operably associated with the motor, a power limit relay connected to said generator and motor and being operable when the regenerated energy exceeds a predetermined value, and means independently 40 responsive to the operation of the reversing switches or the power limit relay for connecting the dynamic braking circuit to the precession motor. 45

4. In a control system for a gyroscopic stabilizer, the combination including a main gyro wheel, a spinning motor operably connected to said wheel, a generator supplying energy to the spinning motor, a prime mover for driving the generator, a direct current generator mechanically coupled to the prime mover, a direct current precession motor operably connected to the main gyro wheel, a control gyro, means cooperating with said control gyro for controlling the operation of the precession motor, said means 60 including anti-hunting means disposed to be operated by the control gyro to prevent hunting of the precession motor. 65

5. In a control system the combination including an electric motor having an armature connected to drive a gyroscope, a generator having an armature and a field winding, means for selectively connecting the said armatures in closed circuit relation to effect any desired direction of rotation for the motor armature, means 70 75

adapted to deenergize the said generator field winding whereby a regenerative braking effect is produced, a dynamic braking circuit, a mechanical brake, means for successively initiating a regenerative braking effect, a dynamic braking effect, and a mechanical braking effect for the motor, and means for reducing the field flux of the field winding of the generator to substan-

tially zero during the action of such braking effects, thereby preventing the circulation of a large amount of current through the armature of the motor when it is brought to rest by said braking effects.
